RAIL SPIKE

Original Filed Feb. 5, 1921

UNITED STATES PATENT OFFICE.

HERBERT O. CRIPPEN, OF JACKSONVILLE, FLORIDA.

RAIL SPIKE.

Application filed February 5, 1921, Serial No. 442,727. Renewed March 8, 1923.

To all whom it may concern:

Be it known that I, HERBERT O. CRIPPEN, a citizen of the United States, residing at Jacksonville, in the county of Duval and 5 State of Florida, have invented new and useful Improvements in Rail Spikes, of which the following is a specification.

This invention relates to an anchoring device for spikes, and more particularly to an 10 improvement over the spike shown in my co-pending application for patent filed September 11, 1920, Serial No. 409,519, and has for its primary object the provision of means for mechanically locking the element in active 15 position and further to hold the element and spike against relative movement in the initial driving of the spike.

An object of the invention is to provide 20 means whereby the spike is more effectively held in an active position.

With these and other objects in view the invention will be better understood from the following detailed description taken in connection with the accompanying drawing 25 wherein:

Fig. 1 is a side elevation showing the anchoring device in active position.

Fig. 2 is a view illustrating the element 30 about to be forced to its active position with the rail.

Fig. 3 is a side elevation of another form of my invention.

Fig. 4 is a rear elevation of that form of 35 my invention shown in Figure 3.

Fig. 5 is a front elevation.

Figs. 6 and 7 are sectional views along the lines 6—6 and 7—7 of Figure 5.

Again referring to the drawing illustrating two forms of my invention and more 40 particularly to Figures 1 and 2. The numeral 1 designates a spike formed with a pocket 2, and a rib 3 at one side of the pocket. The numeral 4 designates an arcuate seat formed at the termination of the rib. 45 The anchoring element 5 has a lug 6 fulcrumed on the seat and has one end formed into a head portion 7 and the other end into a shank terminating into a prong 9. The head portion 7 is provided with a cam edge 50 10, engaging the base flange 11 of the rail with the result that in the driving of the spike the element is swung about the seat 4, so that the head portion moves in one direction, and the shank portion in the opposite 55 direction for penetration into the rail

tie. The element can be of any thickness desired and snugly received in the pocket and lies flush with the surface of the rib 3, so as not to interfere with the driving of the spike. 60

An important feature of my invention is the arrangement of the shoulder 12 which is adapted to slip slightly under the base 11 when the spike is completely driven thereby locking the element and spike against 65 removal. A very important feature is, by locking the spike and element against any movement at all, a tight fit is assured thereby preventing water or moisture from entering between the spike, element and tie 70 which would cause the rotting action, which greatly shortens the life of the tie. Thus it will be seen that the increase in life of the tie will more than pay for the cost of the anchoring device. 75

To prevent dislocation of the anchoring element and also the proper positioning of the element in the initial driving of the spike, I provide a clip 13 which can be of any construction of any material but for 80 the purpose of illustration is shown as a thin band of metal that may be readily ruptured when the cam surface 10 begins to act upon the rail base.

In the remaining views I have provided an 85 anchoring element 14 which has a continuous cam surface 15 and is not provided with the shoulder 12. This construction enables an effective grip between the spike and the tie but allows the spike to be removed with a 90 suitable instrument. For the purpose of locking this form of locking element in an active position, the head portion 16 is formed with a hole 17 for the reception of the tapering pin 18. It is driven into the hole and 95 engages behind the shank of the spike thereby preventing accidental movement of the element. To complete the invention I provide teeth 19 along the shank portion 20 of the element. At this point I wish to call attention to the fact that the pin 18 may be of various other constructions than illustrated and associated with the spike in other manners. 100

From the foregoing description taken in 105 connection with the accompanying drawings it will be seen that I provide a spike and a locking element thereof that has a number of advantages over that shown in my co-pending application to the extent that the 110

element is mechanically locked in active position and besides the element is properly held and associated with the spike in the initial driving of the spike.

- 5 It is, of course to be understood that the spike may be constructed in various other manners than illustrated and the locking element constructed in various shapes than illustrated and associated with the spike in other relations, therefore, I do not desire to be limited in any manner except as set forth in the claims hereunto appended.

Having thus described my invention what I claim is:

- 15 1. In combination with a spike, an anchoring element having a swinging connection with the spike and having a cam head portion moving in one direction by a cam action with a rail, and having a penetrating shank portion moving in an opposite direction for engagement with a tie, and a clip for preventing relative movements of the

spike and element in the initial driving of the spike.

2. In combination with a spike having a seat, an anchoring element having a lug fulcrumed on said seat whereby the opposite ends of the element may swing in opposite direction by a cam action with the rail in the driving of a spike, and a clip for preventing relative movements of the spike and elements in the initial driving of the spike.

3. In combination with a spike having a seat, an anchoring element having a lug fulcrumed on said seat whereby the opposite ends of the element may swing in opposite direction by a cam action with the rail in the driving of a spike, and a clip for preventing relative movements of the spike and element in the initial driving of the spike, and a locking member for the element when the spike has been further driven.

In testimony whereof I affix my signature.

HERBERT O. CRIPPEN.
